RADIO RECEIVER

Katsuhiko Makino, Osaka, Japan, assignor to Matsushita Electric Industrial Co., Ltd., Kadoma-shi, Osaka, Japan

Filed Aug. 4, 1971, Ser. No. 169,153

Term of patent 14 years

Int. Cl. D14—03

U.S. Cl. D56—4 B

FIG. 1 is a top, front perspective view of a radio receiver incorporating my new design;

FIG. 2 is a bottom, front perspective view thereof, as seen from the same side as FIG. 1; and

FIG. 3 is a top, rear perspective view thereof as seen from the opposite side to that of FIG. 1.

Portions of the drawing figures are shaded to indicate contrast and appearance, and portions are diagonally lined to indicate transparency.

I claim:

The ornamental design for a radio receiver, as shown and described.
